Ralph. W. Wilson

Inventor

By his Attorneys Dodson & Raw.

UNITED STATES PATENT OFFICE.

RALPH WM. WILSON, OF NEW YORK, N. Y.

VANITY BOX.

Application filed October 6, 1922. Serial No. 592,706.

To all whom it may concern:

Be it known that I, RALPH W. WILSON, a citizen of the United States, residing at New York, in the county of New York and State 5 of New York, have invented a certain new and useful Improvement in Vanity Boxes, of which the following is a specification.

My invention relates to that class of vanity boxes which are designed to contain 10 a much larger quantity of powder than rouge as it is well known that the use of the two are in a proportion of approximately five to one. It is therefore desirable to provide a vanity box in which the powder will 15 exceed the rouge by about that much.

My invention has for its object to provide a device of this character which will be both compact in size and inexpensive to manufacture, and has for its further object 20 to provide a convenient means for preventing the small particles of rouge which fleck off of the compact when used from getting into the powder compartment.

My means of accomplishing the foregoing 25 may be more readily understood by having reference to the accompanying drawing which is hereunto annexed and is a part of the specification in which:

Fig. 1 is a perspective view of my improved vanity box opened.

Fig. 2 is a side elevation of the box closed.

Fig. 3 is a vertical sectional view.

Fig. 4 is a top or plan view, showing the rouge compartment open and the powder 35 compartment closed.

Similar reference numerals refer to similar parts throughout the entire description.

As shown in the drawings, the device 40 comprises a box 10, the outer wall of which is provided with a shoulder or bead 11. As illustrated, this bead is continuous in form but it is obvious to persons skilled in the art that any projection which will serve as an abutment for the cover 12 will answer the 45 purpose equally well.

The cover 12 is provided with a suitable hinge 13 which is secured to the wall of the box 10 in any convenient or suitable manner.

By making the boxes square, I am able to 50 provide a hinge as long as the width of the box, thereby affording a greater degree of strength than can be obtained in a box where the sides are not flat, though obviously the box does not have to be square. It can be 55 formed in any suitable or desired shape, the

form illustrated being merely the preferred embodiment.

The cover 12 is provided with a peripheral wall 14, which is adapted to telescope the outer wall of the box 10 and abut the bead 60 11. A rouge compact 15 is mounted inside of the cover 12 and a powder compact 16 is mounted in the box 10.

I provide a cover 17 for the compartment containing the powder compact which is 65 provided with a peripheral wall 18 which telescopes the inside of the box 10.

A mirror 19 is provided on the inside of the cover 17.

In this construction, it will be apparent 70 that the user has both the powder and rouge compartments open at the same time and the mirror is conveniently arranged for use, at that time. The cover 17 is preferably provided with an outwardly extending 75 flange 20 which exactly fits the inner surface of the peripheral wall 14 of the cover 12, as clearly seen in the sectional view, Fig. 3. When this cover 17 is closed as in Fig. 4 it is apparent that that portion of the box 80 in which the powder compact 16 is located is entirely closed. A suitable powder puff 21 is mounted in the box 10 intermediate the powder compact 16 and the mirror 19 and a powder puff 22 is provided for use with the 85 rouge compact 15, when the outer cover 12 which contains the rouge compact is closed, any particles or flakes of the rouge which have been dislodged by the application of the powder puff in the hands of the user, 90 will fall upon the back of the inner cover 17 which, since it tightly closes the powder compartment, will prevent the rouge getting into it.

Having described my invention what I 95 regard as new and desire to secure by Letters Patent is:

1. In a device of the character described, the combination with a box having an inner and outer cover hinged at opposite sides of 100 the box, a powder compact in said box, a powder puff for said powder, a mirror mounted inside of the inner cover, a vertical wall on said cover, adapted to telescope inside the vertical wall of the powder compartment of the box, a flange on said inner cover adapted to engage and abut the upper edge of the side wall of the box, an outer cover having peripheral walls which telescope the outside of the side walls of the box 110

and abut the shoulder formed thereon, the flange on the inner cover being fitted to the inside of the wall of said upper cover, a rouge compact on the inside of said outer cover.

5 2. In a device of the character described, the combination with a box having an inner and outer cover hinged at opposite sides of the box, a powder compact in said box, a powder puff for said powder, a mirror mounted inside of the inner cover, a vertical wall on said cover, adapted to telescope inside the vertical wall of the powder compartment of the box, a flange on said inner

cover adapted to engage and abut the upper 15 edge of the side wall of the box, an outer cover having peripheral walls which telescope the outside of the side walls of the box and abut the shoulder formed thereon, the flange on the inner cover being fitted 20 to the inside of the wall of said upper cover, a rouge compact of smaller size than the powder compact on the inside of said outer cover.

In testimony whereof, I have signed the 25 foregoing specification.

RALPH WM. WILSON.
